UNITED STATES PATENT OFFICE.

ROY TAYLOR, OF LOS ANGELES, CALIFORNIA, ASSIGNOR OF ONE-HALF TO DAVID A. CANT, OF LOS ANGELES, CALIFORNIA.

SWIVEL.

Application filed September 2, 1924. Serial No. 735,394.

This invention relates to a swivel for use in a well drilling rig or the like, and it is an object of the invention to provide an effective, improved device of this character.

5 Swivels are used in drilling wells with the rotary method to support the drill stem or kelly in the derrick so that it is free to rotate and to make connection with the kelly so that fluid can be pumped into it. The 10 swivel connects the upper end of the kelly with a travelling block supported from the crown block at the top of the derrick. During 15 operation the kelly and swivel are subject to considerable jarring and whipping action which cause rapid wearing of the swivel and often failure of the swivel.

It is an object of this invention to provide a swivel which will operate effectively and without excess wear.

20 Another object of this invention is to provide a swivel which is universally movable in the bail or carrier.

A further object of this invention is to 25 provide a construction applicable to the ordinary form of swivel to improve its operation and relieve it of wear.

The various objects and features of my invention will be best and more fully understood from the following detailed description 30 of a typical preferred form of the invention, throughout which description reference is had to the accompanying drawings in which

Fig. 1 is a view taken from one side of 35 the swivel with certain parts broken away to show in section.

Fig. 2 is a detailed plan section taken substantially as indicated by line 2—2 on Fig. 1.

40 Fig. 3 is a view taken as indicated by line 3—3 on Fig. 2, the body of the swivel being shown in elevation and

Fig. 4 is a view taken as indicated by line 4—4 on Fig. 2.

In the drawings numeral 10 designates the 45 goose-neck of the swivel, numeral 11 the stem of the swivel and numeral 12 the body of the swivel, which connects the goose-neck and stem. The goose-neck 10 is at the upper end of the body 12 and operates as a fluid 50 conductor for connecting the swivel with a hose, or the like, (not shown). The stem is at the lower end of the body 12 and is adapted to be connected with the upper end of the drill stem, (not shown), by means of

a suitable coupling. The body 12 carries 55 the stem 11 so that it is rotatable and so that it will support the load of the drill stem and connected parts, such as drill pipe, drilling tools, etc. Further, the body 12 forms a fluid connection between the goose-neck 10 and stem 11 whereby fluid supplied 60 to the goose-neck passes through the body and is discharged through the stem into the kelly. The present invention is not specifically concerned with the details of construction, formation, or arrangement of the parts thus far described nor with the details of the bearings, packing glands etc., carried in the body 12 to make the necessary connections between the goose-neck 10 and stem 11. 65 In practice the various parts of the swivel thus far mentioned may be such as are common to devices of this general character.

70 Trunnions 15 extend from the side wall of the body 12 at diametrically opposite 75 points. The trunnions 15 may be formed integrally with the side wall of the body 12 and may be shaped and proportioned substantially the same as the trunnions provided on the ordinary type of swivel to receive the 80 supporting bail.

In accordance with this invention a yoke 85 preferably in the form of a ring 20 is applied to the body 12 to support the body through the trunnions 15. The ring 20 preferably fits around the body with substantial clearance, as illustrated throughout the drawings, and is provided at diametrically opposite points with bearings to receive the trunnions 15. The construction and formation of the ring 20 and bearings in the ring to carry the trunnions 15 may in practice vary considerably. It is preferred that the ring 20 be a continuous ring formed without joints and that the bearings be formed 90 by notching the ring and applying suitable bearing caps 21 to it. In the construction illustrated in the drawings, notches 22 are provided in the ring from its upper end and the bottoms of the notches are shaped 95 to receive the trunnions 15. The bearing caps 21 are arranged in the notches 22 above the trunnions to retain the trunnions in place in the ring. The bearing caps 21 are held by projections 23 extending from opposite 100 sides of blocks into recesses 24 provided in the side walls of the notches 22. The blocks 21 are adapted to be slid into place from 105

the outside of the ring over the trunnions and may be retained in position by cap screws 25.

The ring 20 has trunnions 30 projecting from its outer side at diametrically opposite points. The axis of the trunnions 30 is at right angles to the axis of the trunnions 15 and is preferably located in the same horizontal plane as the axis of the trunnions 15. 5 The trunnions 30 may be formed integrally with the ring 20 and may be shaped and proportioned substantially the same as the trunnions 15. The trunnions 30 are for the purpose of mounting the ring 20 in a supporting bail 33 similar to the bail used for the ordinary swivel. The bail 33 comprises two side parts connected together at their upper ends, and provided at their lower ends with openings 36 to rotatably carry the trunnions 10 30.

In operation the device provided by this invention is used the same as the ordinary swivel. It is supported by a travelling block through the bail 33, a suitable hose 25 is connected with the goose-neck 19, and the drill stem or kelly, is connected with the stem 11. The operation of the swivel is, however, materially different from that of the ordinary swivel. In the case of an ordinary swivel the connection between the body 12 and bails allows for pivotal movement of the body relative to the bail in one direction only, so that movement of the body in any other direction causes movement of the bail 30 with relation to the travelling block. It is obvious that this causes uneven operation of the swivel and operates to cause whipping and irregular movement of the entire swivel. With the construction provided by 40 this invention the body 12 is universally mounted in the bail, being perfectly free to move in any direction and therefore operates uniformly and without the whipping action above referred to. The uniform operation 45 of the device is not only important in improving the operating of the entire drilling apparatus, but also in prolonging the life of the swivel. In practice the construction which I have provided may be applied to 50 swivels at the time of manufacture or may be applied to the usual type of swivel by applying the yoke ring between the body

of the swivel and the bail or by removing the usual bail and applying the yoke ring and a new bail to fit the yoke ring. 55

Having described only a typical preferred form of my invention I do not wish to limit myself to the specific details hereinabove set forth, but wish to reserve to myself any changes or variations that may appear to those skilled in the art or fall within the scope of the following claims: 60

Having described my invention, I claim:

1. A swivel device for rotary drilling outfit, including a body for rotatably supporting a drill stem and having offset trunnions, a ring surrounding the body and receiving said trunnions, and a bail for pivotally suspending the ring. 65

2. A swivel device for rotary drilling outfit comprising in combination with the kelly of the drill stem and the suspending bail, of a universal joint structure supported by said bail and in turn swivelly supporting the kelly of the drill stem. 70

3. A swivel for rotary drilling outfit comprising in combination with the kelly of the drill stem, a swivel body for rotatably supporting the said kelly, trunnions formed on said body, a ring surrounding the body and receiving said trunnions, other trunnions formed on said ring, and a suspending bail pivotally engaging said last named trunnions. 75

4. In a rotary drilling apparatus, the combination with the kelly and the suspended sheave block of the apparatus, of a swivel device for supporting the kelly, and a universal joint connecting said swivel device and sheave block. 80

5. In a rotary drilling apparatus, the combination with the rotatably driven kelly and the sheave block suspended from the top of the derrick, of a swivel device including a swivel for rotatably receiving and suspending the kelly of the drill stem, a universal hanger ring engaging with said swivel and a bail connected to said hanger ring and adapted to be supported by the sheave block. 85 90 95

In witness that I claim the foregoing I have hereunto subscribed my name this 16th day of Aug. 1924. 100

ROY TAYLOR.
